SELF-PRIMING PUMP

Albert J. Granberg, Oakland, Calif.

Application December 26, 1946, Serial No. 717,517

7 Claims. (Cl. 103—113)

1

My invention relates in general to pumps and more particularly to an impeller pump assembly having self-contained priming features.

Among the objects of my invention are:

- (1) To provide a novel and improved self-priming pump assembly;
- (2) To provide a novel and improved self-priming impeller pump assembly;
- (3) To provide a novel and improved impeller pump assembly capable of pulling a high vacuum;
- (4) To provide a novel and improved self-priming pump assembly involving but a single priming valve to control feed of priming liquid to the pump;

(5) To provide a novel and improved impeller pump which may be readily adjusted and serviced;

(6) To provide a novel and improved impeller pump having the ability to scavenge itself of a substantial portion of accumulated air.

Additional objects of my invention will be brought out in the following description of a preferred embodiment of the same taken in conjunction with the accompanying drawings wherein—

Figure 1 is a longitudinal view in section through a pump assembly embodying the features of my invention;

Figure 2 is a view in section taken in the plane 2—2 of Figure 1 and showing the impeller casing partly broken away;

Figure 3 is a view in elevation of a fragmentary portion of the pump assembly of Figure 1;

Figure 4 is a view in section taken in the plane 4—4 of Figure 1;

Figure 5 is a view in section through a gland embodied in the pump assembly of Figure 1;

Figure 6 is an end view of the gland assembly of Figure 5.

For the details of the preferred embodiment of my invention, reference will be made to the aforementioned drawings. The pump assembly being of the impeller-type, it embodies an impeller 1 of more or less conventional design having a plurality of radial passages 3 defined by involute partitions 5 radiating outwardly from the central region of the impeller to the peripheral edge thereof, such passages connecting with an axial inlet passage 7 formed in an axial ex-

tension 9 of the impeller on one side thereof. On the other side, the impeller is formed with the hub 11 for mounting on a drive shaft 13.

The impeller casing is formed of two sections 15 and 17 respectively, bolted together, each having an axial opening countersunk to provide an axial recess for each axial end of the impeller.

The priming chamber 19 is cast integral with the casing section 15 and is provided with a central opening 21 in the roof thereof for initial priming purposes.

Formed alongside the priming chamber and as an integral part thereof is an inlet passage or suction line 23, a portion 25 of which passes through the priming chamber, terminating at the axial inlet passage 7 in the impeller. Such portion of the inlet passage tapers to provide a valve seat. At this point the passage has one or more openings 27 to the interior of the priming chamber whereby an immediate supply of liquid from the priming chamber to the impeller will be available when such openings are exposed to the inlet passage.

Such openings, however, are adapted to be normally closed by a valve 29 involving a tapered ring 31 connected by a plurality of radial spokes 33 to a central hub 35, whereby regardless of the position of the valve, whether it be seated or unseated, it will permit a substantial normal flow of liquid to the pump through the inlet passage.

The valve is mounted on a valve stem 37 extending out of the inlet passage through an opening in the wall thereof. Such opening is covered by a housing 39 bolted into position and provided with a wall 41 extending part way across the opening. Such wall has bolted thereto a baffle or guide 43 at the turn in the inlet passage to avoid turbulence, as the liquid flows through the inlet passage to the pump impeller. Both this wall and baffle are perforated to receive a long bushing 45 through which the valve stem slidably passes.

Pivotedly mounted on a lug 47 depending from the roof of the housing, is a bell crank lever having a vertically directed arm 49 adjustably affixed to the end of the valve stem 37, and a horizontally disposed arm 51 terminating at its end in a weight 53, causing a pull on the stem tending to unseat the valve. The amount of

weight is fixed at a value such as to unseat said valve on the occasion of a drop in the normal pressure of the inflowing liquid against the valve, such drop in pressure being occasioned by a decrease of velocity of such liquid.

Such drop in velocity may be caused either by a diminishing supply of liquid at the source from which such liquid is being pumped or by the undesired introduction of substantial quantities of air into such liquid. In either case, the gases entrained in the liquid entering the impeller will tend to accumulate as gas bubbles along the surfaces of the pump components, and in the absence of precautions will ultimately cause the pump to lose prime. Before this condition can occur, however, in the pump assembly described above, the valve will become unseated and a prompt supply of liquid from the priming chamber will be available.

An involute channel 55 along the inside periphery of the pump casing, terminates in a discharge opening 51 to the priming chamber, and at the top of such priming chamber, a threaded opening is provided for a discharge pipe connection 59. Thus the priming chamber gets first call on the discharge from the pump impeller, and if the source of supply for the pump has run dry, the liquid in the priming chamber will circulate through the impeller and continue to maintain prime in the pump.

Adjacent to and transverse of the periphery of the impeller and lying in the discharge stream, are a plurality of trimmer lugs 61 and 63. The first of these trimmer lugs is shaped to present an inwardly deflecting baffle surface 64 terminating in an edge 65 in close proximity to the impeller rim. The succeeding lug 63 presents a stream-line surface to the flow of liquid and terminates in a relatively sharp edge 66 in skimming relationship to the rim of the impeller.

It is characteristic of impeller-type pumps that a substantial portion of air introduced into these pumps tends to separate out and accumulate as a layer of air bubbles on the outer periphery of the impeller. It is desirable in a pump of this type to either preclude the formation of such bubbles if possible, or effectively remove the same if and when they appear.

The aforementioned trimmer lugs serve this latter function, the foremost of such lugs functioning as a baffle to deflect such air bubbles inwardly of the impeller. This not only frees these bubbles from attachment to the impeller, but in deflecting them inwardly, their tendency to rebound under the action of the fast rotating impeller causes them to acquire sufficient momentum to carry them into the path of the succeeding trimmer lug which skims them off and guides the same into the discharge flow.

By tapering that edge 68 of the casing discharge opening facing the rotational movement of the impeller, and terminating it in skimming relationship to the impeller rim, any of the inwardly deflected bubbles which rebound beyond the second trimmer lug, may be skimmed off.

Such removal of the peripheral layer of bubbles from the impeller, serves to relieve the more inwardly anchored air bubbles of a certain amount of back pressure whereby they become more weakly anchored. The centrifugal action of the impeller can, under these conditions more readily dislodge such bubbles, and this is aided somewhat by such turbulence as is created by the inward deflection of the bubbles from the peripheral layer.

The number of lugs required to reach maximum efficiency in the removal of such air bubbles from the impeller is small, for beyond that point where most of the air has been removed, the addition of more lugs will have little additional effect.

A feature of the priming chamber as described resides in the fact that all openings thereto are above the elevation of the impeller and casing, thereby assuring without reliance upon valves, that the chamber will remain full after each cycle of pump operation.

The section 17 of the impeller casing is in the form of a disc having extending axially therefrom a pair of aligned tubular sections 61 and 69 respectively, connected together by a top rib 71 and angularly disposed base ribs 73, the two sections being thus supported in spaced relationship to each other.

That tubular section 61 provides a housing for a packing gland assembly involving a plurality of layers of packing 75 under pressure of a packing gland 77 mounted on the shaft 13. Such gland is formed of a pair of longitudinal half sections 79 adapted to fit about the shaft within the packing gland housing, each such half section terminating in a complementary lateral flange 81 exposed in the space between the two tubular sections, each such flange being perforated to permit passage of a clamping bolt 83. The length of the gland is somewhat less than the aforementioned spacing to permit withdrawal of the gland sections from the housing and thus provide access to the packing.

The gland is held in functional position against the packing, by suitable holding means. Toward this end, I provide diametrically spaced ears 85 extending laterally from the gland assembly housing, each of these ears being notched to provide anchorage for one of the clamping bolts 83. A retainer cap 87 slidably mounted on that portion of the shaft exposed between the tubular sections, is adapted to fit over the gland, and has bolt openings therethrough matching those in the gland, whereby bolts anchored in the ears 85 might pass and be secured as by a tightening nut 89.

A trough 90 cast integrally with the base ribs 73 below the gland, serves as a catch basin for drippings or the like which might, at some time or another, develop.

A pair of shaft bearings 91 are located in the other tubular section 69 through which the drive shaft passes, and the exposed sides of each of such bearings is covered by a dust seal 93 held in position by a locking ring 95.

These bearings are maintained in properly spaced relationship by a spacing sleeve 97 mounted on the shaft.

Axial adjustment of the impeller 1 in its casing is provided for by cutting a relatively broad circumferential groove 99 in the drive shaft at a point covered by the spacing sleeve, and by means of radially disposed set screws 101 in the sleeve, the sleeve and drive shaft may be locked together at some point within the limits permitted by the width of such groove.

In order that such adjustment may not be disturbed by the influx of liquid to the pump impeller, I provide passages 103 through the impeller hub, which serve to equalize the hydrostatic pressure between the inside and outside of the impeller and thereby largely neutralize the thrust of the incoming liquid against the impeller.

In that tubular section which houses the bearings, I provide a radial opening in line with the drive shaft groove whereby the set screws may be rendered accessible by means of a screw driver, for effecting such aforementioned axial adjustment of the impeller. This opening is preferably threaded for the reception of a grease cup 108 which serves to maintain lubrication of the bearings. When axial adjustments of the impeller are to be made, however, such grease cup may be readily removed for the purpose.

From the above description of my invention in its preferred form, it will be apparent that the same fulfills all the objects as previously recited. Therefore, while I have described such embodiments in considerable detail, I do not desire to be limited in my protection to such details except as may be necessitated by the appended claims.

I claim:

1. A self-priming impeller pump assembly comprising an impeller; a casing enclosing said impeller and having an axial input opening to said enclosed impeller; a priming chamber; an input passage leading to said input opening and having a wall exposed to the interior of said priming chamber, said passage having at least one connecting opening therethrough to the interior of said priming chamber; a valve disposed in said passage, and adapted in its seated position to close said connecting opening, said valve having an opening therethrough to permit substantial normal flow through said input passage and a valve stem extending therefrom through the wall of said input passage; and means adapted to withdraw said valve from seating position upon drop of hydrostatic pressure of flowing liquid against said valve, to expose said connecting opening and permit flow of liquid from said priming chamber into said input passage.

2. A self-priming impeller pump assembly comprising an impeller; a casing enclosing said impeller and having an input opening to said enclosed impeller; a priming chamber; an input passage leading to said input opening and having a wall exposed to the interior of said priming chamber, said passage having at least one connecting opening therethrough to the interior of said priming chamber; a valve disposed in said passage, and adapted in its seated position to close said connecting opening, said valve having an opening therethrough to permit substantial normal flow through said input passage and a valve stem extending therefrom through the wall of said input passage; and means adapted to withdraw said valve from seating position upon drop of hydrostatic pressure of flowing liquid against said valve, to expose said connecting opening and permit flow of liquid from said priming chamber into said input passage, said means including a pivotally mounted bell crank lever having a pair of moment arms at substantially right angles to each other, one of said arms being connected to said valve stem and the other of said arms terminating in a weight sufficient to unseat said valve on the occasion of such drop in hydrostatic pressure.

3. A self-priming impeller pump assembly comprising an impeller; a casing enclosing said impeller and having an axial input opening to said enclosed impeller; a priming chamber adjacent said impeller casing; an input passage through said priming chamber to said casing input opening, said passage having a tapering interior wall adjacent said casing opening to pro-

vide a valve seat, and at least one connecting opening to the interior of said priming chamber through said valve seat; a valve disposed in said passage, said valve having a taper complementary to said valve seat, and an opening therethrough to permit substantial normal flow through said input passage, a valve stem connected to said valve and extending through the wall of said input passage; and means adapted to withdraw said valve from seating position upon drop of hydrostatic pressure of flowing liquid against said valve, to expose said connecting opening and permit flow of liquid from said priming chamber into said input passage, said means including a pivotally mounted bell crank lever having a pair of moment arms, one of said arms being connected to said valve stem and the other of said arms terminating in a weight sufficient to unseat said valve on the occasion of such drop in hydrostatic pressure.

4. A self-priming impeller pump assembly comprising an impeller; a casing enclosing said impeller and having an axial input opening to said enclosed impeller; a priming chamber adjacent said impeller casing; an input passage through said priming chamber to said casing input opening, said passage having a tapering interior wall adjacent said casing opening to provide a valve seat, and at least one connecting opening to the interior of said priming chamber through said valve seat; a valve disposed in said passage, said valve including a ring having a taper complementary to said valve seat, and a central section connected to said ring by a plurality of radial spokes angularly spaced to permit substantial normal flow through said input passage, a valve stem connected to said central section and extending through the wall of said input passage; and means adapted to withdraw said valve from seating position upon drop of hydrostatic pressure of flowing liquid against said valve, to expose said connecting opening and permit flow of liquid from said priming chamber into said input passage, said means including a pivotally mounted bell crank lever having a pair of moment arms at substantially right angles to each other, one of said arms being adjustably connected to said valve stem and the other of said arms terminating in a weight sufficient to unseat said valve on the occasion of such drop in hydrostatic pressure.

5. An impeller pump comprising an impeller, a casing enclosing said impeller, said casing having an axial input opening to said impeller and a discharge opening in the periphery of said casing adjacent the rim of said impeller, and a plurality of stationary trimmer lugs transverse to the rim of said impeller in said opening, certain of said trimmer lugs having a tapered edge in skimming relationship to said impeller rim.

6. An impeller pump comprising an impeller, a casing enclosing said impeller, said casing having an input opening to said impeller and a discharge opening in the periphery of said casing adjacent the rim of said impeller, and a plurality of stationary trimmer lugs transverse to the rim of said impeller, the first of said trimmer lugs having an inwardly deflecting baffle surface terminating in an edge in close proximity to said rim and a succeeding lug having a tapered edge in skimming relationship to said impeller rim.

7. An impeller pump comprising an impeller, a casing enclosing said impeller, said casing having an input opening to said impeller and a discharge opening in the periphery of said casing adjacent the rim of said impeller, and a plurality

of stationary trimmer lugs transverse to the rim of said impeller, the first of said trimmer lugs having an inwardly deflecting baffle surface terminating in an edge in close proximity to said rim, and a succeeding lug having a tapered edge in skimming relationship to said impeller rim, and that edge of said casing discharge opening facing the rotational movement of said impeller also being tapered and in skimming relationship to said impeller rim.
